ANTENNA CONSTRUCTION

Andrew Alford and Morton Fuchs, New York,
N. Y., assignors to Federal Telephone and Radio
Corporation, a corporation of Delaware

Application September 30, 1942, Serial No. 460,290

9 Claims. (Cl. 250—33)

This invention relates to antenna systems and more particularly to vertical antenna arrangements.

One of the objects of this invention is to provide a vertical antenna arrangement having substantially symmetrical radiation and wherein high frequency currents heretofore induced in the supporting structure are greatly reduced if not substantially eliminated.

Another object of this invention is to provide a vertical antenna having radiators of low surge impedance so that a transmission line to be connected thereto may be matched thereto over a wide frequency band.

Still another object of this invention is to provide a sturdy vertical antenna arrangement which is simple in construction, adjustable for different wavelengths.

Vertical antenna arrangements are often mounted on metallic masts with the upper radiator thereof extending above the top of the mast and the lower radiator immediately therebelow but some distance above ground. This arrangement provides dissimilar impedance characteristics for the two radiators resulting in the occurrence of high frequency currents in this supporting mast. In accordance with this invention this difficulty is overcome by extending the mast upon which the radiators are mounted to at least the upper end of the upper radiator. This relationship produces an effect upon the surge impedance of the upper radiator substantially equal to the effect produced on the surge impedance of the lower radiator by the portion of the mast extending therethrough. The symmetry of radiation pattern of the radiators may be further improved by extending the mast a short distance above the upper radiator so that an end effect is established between the mast and the upper end of the upper radiator which is similar to that of the effect between the bottom end of the lower radiator and the portion of the mast extending therebelow to ground. While the mast may either be solid or hollow, the latter is preferred. The transmission line is preferably extended up through the mast to be shielded thereby, to a point between the two radiators to which the conductors of the transmission line are connected. The radiators may be of any suitable shape, but in accordance with a further feature of this invention preferably comprise hollow cylindrical or approximately cylindrical members mounted co-axially about the mast.

The radiation pattern of the antenna arrangement of this invention is enhanced by a proper

selection of the radiator lengths with respect to the wavelength for which the antenna is used. For hollow cylindrical radiators energy radiates inwardly tending to induce a flow of electrical energy along the mast which, with cylindrical radiator, forms effectively a coaxial line, producing an effective shunt to the feed line at the feeding point. By making the radiators each a half wavelength long we discovered that this shunting effect is greatly diminished, if not substantially eliminated. This we believe is because half wavelength radiators provide in effect open ended one half wavelength lines with respect to the mast thereby presenting at the transmission line connections to the radiators a very high or infinite impedance. This improves the impedance characteristics of the antenna as seen from the transmission line.

In accordance with a further feature of this invention, the hollow cylindrical radiator members are preferably so proportioned as to present a fairly low impedance (about 400 ohms or less) as viewed from the point of the transmission line connections thereto. To match this low surge impedance with a two-wire transmission line we construct the transmission line in the form of an aperiodic impedance transformer made in several sections.

For a further understanding of the invention, reference may be had to the following detailed description to be read in connection with the accompanying drawing, in which,

Fig. 1 is a perspective view with parts in section of one form of dipole antenna in accordance with this invention;

Fig. 2 is a fragmentary view in vertical elevation of another form of antenna system of this invention with parts broken away; and

Figs. 3 and 4 are cross-sectional views taken along lines 3—3 and 4—4 respectively of Fig. 2.

Referring to Fig. 1 of the drawing, antenna comprises two hollow cylindrical radiators 10 and 12 mounted in co-axial relation on a mast 14. The mast 14 is hollow and is provided with an opening 16 adjacent the base thereof through which a transmission line 18 from either a transmitter or receiver 20 is extended. The transmission line extends upwardly in the hollow mast to and through an outlet opening 22 for connection to the upper and lower radiators 10 and 12. The size of the radiators 10 and 12 are preferably so selected as to have a fairly low impedance of about 400 ohms or less as seen at the connections thereof to the transmission line. The transmission line thus may be so selected in wire

size and the spacing of the wires as to substantially match the surge impedance of the radiators, or the line may have a matching impedance transformer at the antenna end thereof, or the line may comprise a known form of aperiodic impedance transformer having periodic occurring sections as indicated by the tapering portions 26. By this latter arrangement impedance matching of the antenna structure over a relatively wide range of frequencies is accomplished.

The mast 40 is extended above the upper radiator 10 a distance L_1 sufficient to provide an upper end effect to balance the end effect produced between the bottom end of the lower radiator 12 and the portion of the mast L_2 . The length L_1 need only extend a few inches above the upper radiator since very little change in the end effect is produced when this extended portion of the mast is increased beyond six inches for half wavelength radiators.

The radiators 10 and 12 may be of almost any desired length from about one-tenth of a wavelength to more than one-half of a wavelength. Radiators one-half wavelength long, however, give the most efficient operation as hereinbefore explained, that is, for this length the shunting effect caused by the coaxial line is substantially eliminated. While we prefer the half wavelength, the radiators may be of shorter length, but less efficiency will be experienced.

For a quarter wavelength, for example, an open quarter wavelength line effect will be had between the radiators and the mast. This lowers the impedance at the line connection and a short circuit effect results giving a voltage distribution substantially as shown by the dot-and-dash lines 30 and 31. For radiators one-half wavelength long, the voltage distribution curves are substantially as indicated by the broken lines 32 and 34. The latter voltage distribution effects are substantially symmetrical and provide in effect a desired horizontal radiation lobe pattern as indicated by the line 35.

In Figs. 2, 3 and 4, we have shown another form of antenna construction of this invention wherein the radiators can be adjusted in length for operation at different wavelengths, it being understood, of course, that effective radiator lengths equal to one-half of the wavelengths are preferred for the sake of efficiency and symmetry of the radiation pattern. The mast 40 is preferably cylindrical and supports an upper radiator 41 and a lower radiator 42 of the form illustrated in Fig. 1. The radiator constructions are identical and a detailed description of the lower radiator 42 will suffice.

In order to provide for lengthwise adjustment of the radiator 42, the radiator is made up of two telescoping substantially cylindrical sections 43 and 44. The inner section 43 comprises a 12-sided sleeve while the outer section 44 comprises a 6-sided or hexagonal sleeve. We find that radiator sleeves of this shape are easily constructed from sheet material by a relatively simple stamping operation, the sleeve being made up of three pieces having edge flanges 46 and 47 which when assembled together are secured by any suitable method such as soldering, brazing, welding, etc. The inner sleeve 43 is tightly mounted on the mast 40 by means of annular insulators 50 and 54. The insulator 50 is supported on the sleeve by a bracket 52 and bolts 53. The larger insulator 54 is mounted about the mast by means of a supporting ring 55 bolted to the inner peripheral portion of the insulator

54. Mounted to the outer peripheral portion of the insulator 54 is a metal ring 56 to which a series of studs 57 are secured through openings contained in the insulator. The inner sleeve 43 is secured as by welding to the ring 56. At the outer edge of the ring is mounted a reinforcing sleeve 58 which is adapted to receive along the inner surface thereof the end of the outer sleeve 44.

10 When it is desirable to increase the effective length of the radiator 42, the outer sleeve 44 which is coaxially mounted on the mast 40 by an insulator 59 similar to the insulating support 54, may be telescoped axially with respect to the inner sleeve 43. The two sleeves are normally held together by wing bolts 60 which are secured to the inner sleeve 43 by nuts 61, Figs. 2 and 3, the outer sleeve 44 being provided with slots 63 through which the wing bolts 60 extend. To move the outer sleeve 44 with respect to the inner sleeve 43, the wing bolts 60 are loosened. The mounting of the outer sleeve on the mast at the insulator 59 is sufficiently loose to permit telescoping movement of the sleeve 44. When a desired length is obtained, the wing bolts 60 are tightened thereby maintaining the two sleeves at the desired overall length.

15 The connections between the transmission line 10 to the two radiators is brought out of the mast 40 through a sealed outlet connection shown in cross-section in Fig. 4. This outlet connection comprises two outlet openings 71 and 72 each of which is provided with a peripheral flange 73. Mounted on the flange is a gasket 74 and an insulator 76 which is secured to the flange 73 by studs 71. The center portion of the insulator 76 is provided with a terminal connection 80 which extends therethrough the connection having an axial opening through which to receive one of the wires 82 of the transmission line 10. The wire 82 may be preferably clamped to the connector 80 by a nut 83 and then connected to one of the studs 57 threadably received in the metal ring 56.

20 From the foregoing it will be clear that the antenna construction is sturdy, easily manufactured, and provides for adjustment axially thereof for different wavelengths. It will also be clear that the radiator construction is weather repellent, that is, the inner portion thereof is sealed so that rain, snow and other foreign substance will not enter the interior of the radiators and the mast. This antenna construction may also be used as a parasitic antenna, it being adjusted to the proper wavelength by adjusting the length of the radiators.

25 While we have shown and described only two embodiments of the invention, we recognize that many antenna systems of other designs and arrangements may be made incorporating the symmetrical radiation and impedance matching features thereof without departing from the invention. It will be understood, therefore, that the embodiments herein shown and described are to be regarded as illustrative of the invention only and not as restricting the appended claims.

30 What we claim is:

35 1. A vertical antenna comprising a conductive mast, two radiators surrounding said mast, one disposed above the other and spaced apart a relatively short distance, said mast extending a distance above the upper end of the upper radiator to produce an effect on the impedance of the upper radiator substantially similar to the

effect produced by the lower portion of the mast on the lower radiator.

2. The vertical antenna defined in claim 1 wherein the radiators comprise hollow substantially cylindrical members mounted co-axially with respect to the mast.

3. The vertical antenna defined in claim 1 wherein each of the radiators comprise a pair of telescoping sleeves whereby the axial length of each radiator can be adjusted.

4. The vertical antenna defined in claim 1 wherein each of the radiators is electrically substantially a half wavelength long.

5. A vertical antenna comprising a conductive mast, a shielded transmission line extending to a given point up on said mast, two radiators each surrounding said mast and connected to said transmission line, one of the radiators being disposed a relatively short distance above said point and the other disposed a relatively short distance below said point, and said mast having a portion extending above the upper radiator to produce an upper end capacity effect substantially similar to an end capacity effect produced at the bottom of the lower radiator by the portion of the mast extending therebelow.

6. The vertical antenna defined in claim 5 wherein the two radiators comprise hollow sleeves of a size having a relatively low surge impedance and said transmission line being constructed to substantially match the surge impedance of said radiators.

7. A vertical antenna comprising a hollow conductive mast, a transmission line extending upwardly in said mast so as to be shielded

thereby, two hollow substantially cylindrical radiator members disposed in end to end relation to each other and co-axially with respect to said mast, said transmission line being connected to said radiators, and said radiators being so disposed with respect to the length of said mast that a portion of the mast extends above the upper radiator sufficient to produce a capacity effect therewith substantially equal to the capacity effect produced with the lower radiator by the portion of the mast extending below the lower radiator.

8. A vertical antenna comprising a hollow conductive mast, a transmission line extending upwardly in said mast so as to be shielded thereby, two hollow substantially cylindrical radiator members disposed in end to end relation to each other and co-axially with respect to said mast and spaced apart a relatively short distance, said transmission line being connected to said radiators, said two radiators being of a size having a relatively low impedance and said transmission line being constructed of a plurality of aperiodic impedance transformer sections to substantially match the surge impedance of said radiators over a wide frequency band.

9. The antenna defined in claim 8 wherein each of the radiators are adjustable in length and a change in the surge impedance thereof due to a change in length can be matched at the transmission line connection by shifting the connection with respect to one of the transformer sections of the line.
